Primary Examiner — Kevin K Rudzinski*Assistant Examiner* — Clare Ann Gannon(74) *Attorney, Agent, or Firm* — Christopher Pilling(57) **CLAIM**

The ornamental design for a tri-fold mat, substantially as shown and described.

DESCRIPTION

FIG. 1 is a perspective view of a tri-fold mat showing my new design;

FIG. 2 is a top view thereof;

FIG. 3 is a front view thereof, the rear side view being a mirror image thereof; and,

FIG. 4 is a left view thereof, the right side view being a mirror image thereof.

The bottom view is not visible during use.

The broken lines show unclaimed subject matter only and form no part of the claimed design.
